UNITED STATES PATENT OFFICE.

SIDNEY O. DICKINSON, OF MANILA, PHILIPPINE ISLANDS.

FIBER STRIPPING AND CLEANING MACHINE.

No. 900,494.

Specification of Letters Patent.

Patented Oct. 6, 1908.

Application filed July 16, 1907. Serial No. 384,084.

To all whom it may concern:

Be it known that I, SIDNEY O. DICKINSON, a citizen of the United States, residing at Manila, Philippine Islands, have invented 5 new and useful Improvements in Fiber Stripping and Cleaning Machines, of which the following is a specification.

This invention is an improved fiber stripping and cleaning machine especially adapted for use in stripping and cleaning the fiber of hemp, and it consists in the construction, 10 combination, and arrangement of devices hereinafter described and claimed.

One object of the invention is to provide 15 improved means for stripping the fiber.

Another object is to combine with the fiber stripping means means for pulling the stock and exerting even tension thereon to prevent the breaking of the weaker fibers.

20 A further object is to combine with the fiber stripping mechanism, scraping and cleaning means of improved construction to remove the pulp and juices from the stripped fiber and prevent the fiber from being injured by the souring of such juices.

25 A further object is to provide, in combination with the stripping and scraping or cleaning mechanisms, means for drying the stripped and cleaned fibers prior to the discharge of the same from the machine.

30 A further object is to provide an improved machine of this character which strips the fiber without breaking the same and enables long fibers to be obtained.

35 In the accompanying drawings:—Figure 1 is a perspective view of a fiber stripping and cleaning machine embodying my invention, Fig. 2 is a vertical longitudinal sectional view of the same, Fig. 3 is a vertical 40 transverse sectional view of the same, taken on the plane indicated by the line 3—3 of Fig. 2, Figs. 4 and 5 are detail elevations of the serrated stripping knives.

45 The frame 1 may be of any suitable construction. At the front end of the frame and supported upon suitable cross bars 2, with which the frame is provided, is a horizontally disposed feeding table or plate 3, which extends longitudinally of the frame 50 1 for a suitable distance from its front end and also extends transversely of the frame from side to side thereof. The said table or plate is provided with suitable openings 4 of suitable size and appropriately spaced apart, the said openings being here shown as longitudinal slots.

At the side of the frame 1, at a point over the table or plate 3, are vertically disposed guides 5, which serve to hold and vertically guide a vertically movable frame 6, which frame is provided with a series of stripping blades 7, 8, and 9, appropriately spaced apart and disposed transversely above the plate or table 3. The frame 6 is provided with vertical arms or standards 10 at its 60 sides, which operate in the guides 5. Each of the stripping blades is weighted at its upper side to make it sufficiently heavy for the work it is to perform. The primarily acting blade 7 and the secondarily acting blade 70 8 are provided at their lower edges, which bear on the plate or table 3, with serrations, the serrations of the blade 7 being larger than those of the blade 8. The lower edge of the blade 9 is plane. It will be observed 75 by reference to Fig. 3 that the serrations of the blades 7 and 8 bear on the plate or table 3 at points between the openings therein.

Closely behind the table or plate 3 is a 80 pair of fiber pulling or feed rollers 11—12, the former disposed above the latter. The axle or shaft of the roller 12 is journaled in fixed bearings 13, which are secured on the frame 1. Said roller is provided at one end 85 of its axle or shaft with a suitable pulley 14 for engagement by a suitable power belt, whereby said roller may be rotated to cause the roller 11 to also rotate by bearing thereon. The shaft or axle of the roller 11 is 90 journaled in bearings 15, which are vertically movable in guide standards 16, which are secured on and rise from the sides of the frame. The said guide standards are provided with bearing screws 17, which bear 95 upon the upper sides of the vertically movable bearings 15 and may be adjusted to cause the roller 11 to bear with any desired degree of pressure above the lower roller 12.

At a suitable distance in rear of the prime 100 acting rollers 11 and 12 is a pair of similar rollers 18—19, the former above the latter. The bearings 20 for the lower roller 19 are fixed. The bearings 21 for the upper roller 18 are vertically movable in vertical guide 105 standards 22, which guide standards are provided with adjusting bearing screws 23 to regulate the pressure between said rollers 18 and 19. For the purposes of this specification the rollers 18 and 19 are termed secondary pulling rollers. The lower rollers 12—19 are connected by an endless carrier belt 24,

the said belt also serves to impart rotation to the rollers 18-19, as will be understood. Any other suitable means may, however, be employed to rotate said rollers and I do not limit myself in this particular.

In rear of the secondary pulling rollers 18-19 is an inclined bed 24, here shown as supported on a cross bar 25 and having side plates 26 which are attached to the sides of the frame. A scraping blade 27, which is preferably made of wood and has its lower narrowed edge plane, is supported at its ends in a pair of inclined guides 28.

A lever 29 is provided for raising and lowering the frame 6 and the stripping knives which it carries. Said lever is attached to one end of a rock shaft 30, which is journaled in bearings 31 at the upper ends of the guide standards 5 and is provided with rock arms 32. Said rock arms are connected by links 33 to the arms or standards 10 of the stripper blade frame. It will be understood that by means of said lever 29 and its connections the stripper blade frame may be raised or lowered to raise the stripper blades or lower the same to cause the same to press with any desired degree of force on the plate or table 3. The scraping blade 27 may be raised or lowered by means of a lever 34. The said lever is attached to one end of a rock shaft 35 which is journaled in bearings 36 on the sides of the frame 1 at a suitable distance from the rear end of said frame. Said rock shaft is provided with rock arms 38 which are connected by links 39 to the said scraping blade 27. Said scraping blade when lowered bears against the inclined bed 24 and may be caused to exert any desired degree of pressure on the fiber which has been treated by the stripping knives and fed to said inclined bed by the primary and secondary pulling rollers and the carrier 24. In rear of the said bed 24 is a pair of discharging rollers 40-41, the former above the latter and having vertically movable bearings 42 which operate in guide standards 43. The bearings 44 for the lower roller 41 are fixed, as shown. In rear of the lower discharge roller 41 is the upper end of an inclined receiver 45, which serves to convey the stripped and cleaned fiber to any suitable receptacle. The upper end of the said receiver is here shown as attached to a pivot rod or bar 46, which has its bearings in the sides of the frame 1. A supporting segment bar 47 is pivotally connected, as at 48, to the said receiver at a point near the lower end thereof and operates in a guide and detent 49. The said segment bar is serrated on its lower side to provide teeth 50, which by engagement with the lower side of said guide and detent co-act therewith to support the said receiver at any desired inclination.

The rollers 40-41, in addition to performing the function of discharge rollers for

drawing the fiber between the scraping blade 27 and bed 24 and thereby causing said blade to scrape and clean the fiber, also act as driers. In practice the said rollers 40-41 are maintained in a heated condition by any suitable means and at a suitable temperature. For the purpose of this specification the rollers 40, 41 are shown as hollow and provided with perforated pipes 40^a, 41^a to discharge steam into such rollers to maintain them at the required temperature. The roller 41 is here shown as provided with a pulley 51 for engagement by a suitable power belt, whereby to rotate said roller 41 and hence also the roller 40 which operates thereon.

The operation of my improved fiber stripping and cleaning machine is as follows: The hemp strips, after they have been initially prepared in the customary way, are placed on the plate or table 3 under the stripping knives and with their rear ends far enough between the rollers 11 and 12 to be firmly gripped between them, the said stripping knives being raised while thus placing the hemp-strips and being lowered on the same after the ends of the hemp strips have been thus gripped between the said rollers. The machine being then started the rollers 11 and 12, being rotated in the directions indicated by the arrows in Fig. 2, serve to pull the hemp strips between the bed or plate and the lower edges of the stripping blades. The serrations of the blade 7 being larger than those of the blade 8 the hemp strips are treated by said blades successively, the blade 8 serving to divide the fibers more finely than the serrations of the blade 7. Said blades, in addition to dividing the fibers, serve to strip the pulp therefrom and serve to press the pulp from the fiber, the pulp, which is thus pressed from the fiber, passing through the openings 4 in the plate or table 3. The plane stripping blade 9, which acts last on the fiber, serves to remove such pulp therefrom as escapes the said serrated blades. It will be observed that the prime acting pulling rollers 11 and 12 are disposed closely in rear of the co-acting stripping knives or blades and plate or table, so that they catch the fiber closely behind the rearmost stripping blade 9 and prevent such tension from being exerted on the fiber as to break the same. The rollers 18-19 engage the fiber at a short distance behind the rollers 11 and 12 and also serve to pull upon the fiber, the conjoint action of the said sets of rollers being such as to exert the pulling tension on the fibers at various points of the length thereof, so that the fiber is under substantially uniform tension from end to end while passing through the machine, is engaged at a number of points, is not subjected at any point to destructive tension, and hence said fiber is not broken and passes through the machine and is discharged there-

from in entire lengths, which is a very material improvement and produces fiber of fine quality. After passing between the secondary pulling rollers 18-19 the stripped fiber is directed downwardly by gravity, and also by the movement imparted to the fiber by the pulling rollers over the inclined bed 24 and under the scraping blade 27. The action of the said scraping blade is such as 10 to clean such pulp as may still adhere to the fiber therefrom. After passing the said scraping blade, the fiber passes between the rollers 40-41, which serve to discharge the same and to facilitate the action of the said 15 scraping blade, and the said rollers being maintained in a heated condition, as hereinbefore stated, serve to dry out such pulp and juice as may still adhere to the fiber, so as to entirely rid the fiber of the pulp and juice 20 and prevent injury to the fiber by the action of the acids developed by the souring of the juice. From the rollers 40-40 the fiber, after having been thus stripped, scraped, and dried, passes by gravity down and over the receiver 45 and is discharged therefrom to a suitable receptacle.

Having thus described the invention what is claimed as new, is:—

1. In a machine of the class described, in combination with fiber stripping and pulling mechanisms, an inclined bed to which the fiber is fed by the pulling mechanism, a scraping blade also inclined and converging to the lower discharge end of said bed, means 30 to adjust said blade and means in rear of said bed to discharge the fiber therefrom.

2. In a machine of the class described, the combination of a plate or table having openings, a plurality of stripping blades to bear on the same and having serrations at their bearing edges varying in size in the respective blades, and means to pull the stock between said plate or table and the bearing edges of said blades.

3. In a machine of the class described, in combination with fiber stripping and pulling mechanisms, an inclined bed to which the fiber is fed by the pulling mechanism, a scraping blade also inclined and converging to the lower discharge end of said bed, means to adjust said blade, means in rear of said bed to discharge the fiber therefrom and an inclined receiver in rear of such discharging means, and provided with means whereby the inclination of such receiver may 55 be varied.

4. In a machine of the class described, in combination with fiber stripping and pulling mechanisms, a bed to which the fiber is fed by the pulling mechanism, a scraping 60 blade to bear on said bed, means to raise and lower said scraping blade and vary the pressure thereof, and heating and drying rollers in rear of said bed and scraping blade engaging the fiber in rear of said bed and 65 scraping blade.

In testimony whereof, I affix my signature in presence of two witnesses.
